UNITED STATES PATENT OFFICE.

FREDERICK L. FULLER, OF ILION, NEW YORK, ASSIGNOR TO REMINGTON ARMS COMPANY, INC., A CORPORATION OF DELAWARE.

DESIGN FOR A CASH-REGISTER.

59,735.

Specification for Design.

Patented Nov. 22, 1921.

Application filed June 11, 1921. Serial No. 476,940. Term of patent 14 years.

To all whom it may concern:

Be it known that I, FREDERICK L. FULLER, a citizen of the United States, residing at Ilion, in the county of Herkimer and State of New York, have invented a new, original, and ornamental Design for a Cash-Register, of which the following is a specification, reference being had to the accompanying drawing, forming part thereof.

Figure 1 is a front elevation of a cash register, showing my new design;

Fig. 2 is a side elevation of the same cash register.

I claim:

The ornamental design for a cash register, as shown.

In testimony whereof, I have signed my name hereto this 8th day of June, 1921.

FREDERICK L. FULLER.
